UNITED STATES PATENT OFFICE.

WILLIAM SAWYER, OF NEW YORK, N. Y., ASSIGNOR TO EASTERN ELECTRIC MANUFACTURING COMPANY, OF MIDDLETOWN, CONNECTICUT.

ELECTRIC LAMP.

SPECIFICATION forming part of Letters Patent No. 235,459, dated December 14, 1880.

Application filed September 20, 1880. (No model.)

To all whom it may concern:

Be it known that I, WILLIAM SAWYER, a citizen of the United States, residing at New York, in the county of New York and State of New York, have invented certain new and useful Improvements in Electric Lamps; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

10 My invention relates to electric lamps in which the working parts are inclosed in a tube or globe filled with nitrogen gas and hermetically sealed; and it consists, essentially, in a spring surrounding the electric conducting-wire and automatically actuating a contact piece or nut, so that the metallic contact between the nut and contact-connection of the lamp will be insured if the lamp should be moved up or down on the bracket, or be accidentally turned or loosened on said bracket.

15 It further consists in a chambered or recessed bracket for receiving an insulating cup or receptacle containing the actuating-spring and the terminal of the conducting-wire.

20 It finally consists in details of construction that will be hereinafter more fully set forth in the specification, and pointed out in the drawings, in which—

25 Figure 1 is a section (partly in elevation) of my improved lamp, showing the nut on the conducting-wire and the lamp-connection separated; Fig. 2, the same, showing the nut and lamp-connection in contact. Fig. 3 is a detail view of the insulating-cup.

30 Like letters of reference refer to like parts in the several figures.

Heretofore in electric lamps of this nature it has been difficult to obtain perfect lamp-connections, especially when the lamp becomes 45 turned or accidentally loosened on the bracket, and in order to remove the difficulties before experienced I keep the contact-piece attached to the conducting-wire in constant and strong contact with the lamp-connection.

40 In the accompanying drawings, A represents

a bracket, through which is carried an insulated flexible conducting-wire, E. The outer end of the bracket is bored out or chambered, so as to leave a shoulder at the bottom of the chamber. Within this chamber is placed a 55 perforated insulating-cup, F. The exterior part of the end of the bracket is screw-threaded for the reception of the lamp. The opening in the bracket-arm and insulating-cup is sufficiently large to allow some play to the wire. 60

Within the insulating-cup and around the conducting-wire E is placed a stiff coiled spring, G. One end of the spring is secured or rests on the base of the jacket, the opposite end being in contact with the washer or nut 65 D, which is screwed on the end of the conducting-wire, or may be secured to said wire in any other suitable manner. The spring G serves to keep the nut D in constant and perfect contact with the lamp-connection, and serves to 70 give elasticity to the connecting-points; for if the lamp is turned on the bracket there is space enough within the cup F for the spring and wire to move, and the lower opening in the insulating-cup is sufficiently large to allow ample play for the conducting-wire. Thus it will be seen that as the lamp is moved upward on the bracket the spring acts to force up the nut 75 against the lamp-contact.

In the lamps heretofore constructed the 80 bracket and contacts are rigid, and the circuit is made by screwing down the lamp on the bracket until the contacts meet, and there is a complete circuit so long as the lamp is kept in this position. If, however, the lamp be accidentally turned or loosened, a poor contact occurs, with the attendant results, such as a concentration of the current at the point of contact always produces. In the device here presented this breaking of the contact, and 85 consequently of the circuit, is avoided, for, as before explained, the spring acts to keep the connections constantly in contact.

The insulating-cup F, which may be of any suitable insulating material, may extend 95 slightly above the surface of the bracket-chamber, so as to prevent any short-circuiting between the nut D and the bracket.

In order to secure the lamp from being unscrewed, a spring-catch on the bracket may 100

engage with the base of the lamp and hold it securely in position; or a set-screw, H, may be used for that purpose.

The insulating-cup F may, if deemed necessary, be cemented to the sides of the chamber in the bracket. The wire E, nut D, and contact C lead to one side of the lamp, and the bracket A and base of lamp lead to the other side of the lamp.

10 Having thus described my invention, what I claim is—

1. In an electric lamp, the combination of the contact-piece of the base with a lower contact-piece actuated by a spring secured in an insulating-jacket within the lamp-bracket, whereby the contact between said contact-pieces is constantly and automatically maintained, substantially as described.

15 2. The combination of an electric lamp with a bracket-support having a chamber to receive a perforated insulating-cup surrounding the conducting-wire, and a spring actuating one of the contact-pieces, substantially as described.

20 3. The combination, with an electric lamp having a screw-threaded base, and a chambered bracket-support screw-threaded to receive the base of the lamp, of a perforated insulating-cup, which rests in the chamber of

the bracket, and adapted to receive one end 30 of the conducting-wire, and a spring actuating one of the contact-pieces of the lamp, substantially as described.

4. The insulating-cup F, seated in a chamber of the bracket A, substantially as de- 35

5. The wire E, screw-threaded to receive a contact-nut, D, automatically actuated by a spring surrounding said wire, substantially as described.

40 6. The combination of the lamp-base, having a rigid contact-piece, with the bracket containing an insulating-jacket, and an automatically-movable contact within said jacket, substantially as described, and for the purpose 45 set forth.

7. In an electric lamp, the combination of the screw-threaded base, having a rigid contact-piece, with a chambered bracket, an insulating-cup, and a movable contact-piece actuated by a spring inclosed in said cup, substantially as described.

45 In testimony whereof I affix my signature in presence of two witnesses.

WM. SAWYER.
